CONTROL DEVICE

Carl G. Kronmiller, Minneapolis, Minn., assignor
to Minneapolis-Honeywell Regulator Company,
Minneapolis, Minn., a corporation of Delaware

Application June 17, 1942, Serial No. 447,346

17 Claims. (Cl. 200—83)

The present invention relates to a control device, and more particularly to such a device comprising novel safety features and means for lowering operating pressures in such structure.

In control devices in electrical circuits, for de-energizing the same upon the occurrence of an undesirable condition, it is common practice to use a pressure operated electric switch. This switch remains in closed position as long as the pressure is below a predetermined desired value, and is opened when the pressure exceeds this value. Hence, the pressure generating means may respond in some way to the heating of a burner, or the like, to cause shutdown of the system upon the occurrence of high temperature with a resulting high pressure in a temperature sensing capsule of the volatile fluid filled type. However, if one of the operating parts should rupture due to high pressure or deterioration, the switch will be left in the "on" position and no protection is afforded thereby.

An object of this invention, therefore, is to employ in a temperature responsive device an actuating pressure medium which operates at relatively low pressures to thereby reduce the danger of bursting of parts and to obviate the necessity for bulky mechanism.

Another object of my invention is to provide a temperature responsive device subject to an actuating pressure medium having a relatively low boiling point so that the expansive force of the medium in a gaseous form may be used in the operating range of the device and the pressure medium further providing substantial pressure even at very low temperatures so as to thereby prevent a shutdown of the system due to lack of pressure or expansion of the actuating medium at the low temperatures.

Another object is to provide auxiliary linkage to positively open the limit switch if parts of said device should burst or deteriorate so as to cause the actuating fluid to leak out of the actuating parts and thereby reduce the pressure force of the actuating medium.

A further object is to provide supplemental means to cause operation of the auxiliary linkage to open the switch as a result of an undesirable extreme condition at the pressure generating capsule accompanied by a failure of the normal high pressure cutout portion of the device to operate properly due to binding or failure of parts thereof.

It is also an object of my invention to provide a novel double spring tension means whereby the temperature at which the auxiliary linkage

will open the limit switch may be adjusted with greater exactitude.

Another object resides in the combination of functions of parts set forth in the preceding objects to provide a control device having optimum safety characteristics.

Other objects reside in the novel arrangement of parts of the present structure and will be in part obvious or pointed out in the accompanying specification and claims.

In the drawing.

Figure 1 is an elevational view of a preferred form of my invention with some of the actuating parts shown in section, and,

15 Figure 2 is a pressure-temperature chart of one fluid which may be used with my structure. Referring now to Figure 1, the reference character 10 represents a switch casing having a mercury switch 11 therein which has a suitable mercury fill 12 for bridging electrodes 13 and 14. The mercury switch 11 is carried by a clip 15 which is suitably secured to an arm 16. The arm 16 is in turn secured to a pivot 17 which is formed so as to extend horizontally out from the rear of the casing 10. The arm 16 has a pin 18 at its lower end by which the member 16 is rotated.

An actuating member 20 is pivoted upon a knife edge 21. The member 20 is biased so as to 30 rotate in a clockwise direction by a pair of adjustment springs 25 and 26, which are suitably secured to upstanding ears 27 and 28, respectively, upon the base 29 of the actuating member 20. The spring 25 is the main adjustment spring and is stronger than the spring 26. A suitable adjustment screw 30 is secured to the upper part of the spring 25 and when rotated is adapted to either increase or decrease the tension therein. A suitable guide and indicator 31

40 extends exteriorly to the casing 10 and cooperates with a scale plate 32 to indicate the setting of the main spring 25. The spring 26 is adapted to give a finer adjustment and is a weaker spring than the spring 25. An adjustment screw 35 is

45 secured to the upper part of the spring 26 and is adapted upon rotation to either increase or decrease the tension therein. An arm 36 extends exteriorly of the casing 10 and cooperates with the scale plate 32 to indicate the adjustment of the spring 26. From the foregoing it is seen that an adjustment is provided for giving a first rough adjustment through the relatively heavy spring 25 and for thereafter adjusting the temperature value at which the switch will operate 50 to a nicety by a weaker spring 26.

The base portion 29 of the switch actuating member 28 is adapted to be moved between upper and lower ears of a stop member 40. This stop member is provided so that the mercury switch 11 will not be rocked to an extreme position but will be kept within a certain desired angle of operation. A leveling means 45 is shown as mounted freely upon a post 46 and cooperates at its lower end with a mark 47 upon the casing 10 to indicate when the entire device is leveled properly so that the switch 11 will operate properly within this predetermined limit of movement.

The actuating member 28 is adapted to be rocked by a pressure responsive means generally indicated by the reference character 58. The pressure responsive member 58 comprises a casing 51 which is suitably secured to the casing 10 by a flange 52. Within the housing 51 is a bellows 53 which is secured at its upper portion to a mounting plate 54 and at its lower end to a movable head 55. The head 55 is suitably secured to a stem 56 which is fixed to a cone member 57 that cooperates with a crater 58 in the actuating member 28. Pressure for actuating the bellows 53 is generated in a capsule 60 which may be partially filled with a suitable volatile fluid, such as propane. Adjustment means for determining the initial pressure to be exerted in order to cause movement of the bellows 53 is determined by a spring 61 and an adjusting nut 62 which is screw-threadedly mounted into the upper assembly plate 63 for the pressure motor structure 58. By rotating the screw 62, the spring 61 is more or less tensioned to determine the proper operating pressures for the bellows 53.

All of the structure discussed above in connection with my novel switch mechanism is made of light material. By such structure the cost of production is kept low, together with ease of forming the parts. To make it possible to use smaller parts in my device, I have used what may be termed a fade-out fill for the pressure generating means 60 which actuates the pressure motor 58. By using such a fill, my structure can be used at relatively high temperatures while still not creating correspondingly high pressures. For example, in Figure 2, I have shown a chart disclosing the temperature and pressure characteristics of the fluid propane upon its boiling. It will be understood that the pressures to be referred to hereinafter can be varied without departing from the spirit of my invention. Also it will be understood that certain variations in pressure will not seriously affect the operation of my device as these variations may be compensated for by my adjustment spring structure.

Referring now more in detail to Figure 2, I have shown on the lower left-hand corner of a temperature pressure chart the curve for saturated propane. It will be noted that the saturated fluid will exert different pressures at different temperatures and that the rate of pressure increase rises at a relatively great rate upon the increase in temperature. In my novel switch structure I use just enough propane fluid so that it will boil out completely and change into a gas in the neighborhood of 20° F., as indicated on the chart. After this fluid has changed completely into a gas, the pressure and temperature curve will take the form of substantially a straight line and follow the temperature pressure curve of expansion of a gas. This curve is

shown as a straight line extending off toward the upper right-hand corner of the chart.

It may be assumed that my novel control structure is to be used to control the limit in the bonnet 5 of a hot air furnace. In such structure, the bulb 60 will be placed in the bonnet and the casing 10 may be suitably secured at any desirable place, for example, upon a control panel adjacent the burner or at some other position as desired by the user thereof. It is desirable in such furnaces that the temperature in the bonnet thereof shall not exceed a certain predetermined value, for example, 150°. In other words, if the temperature increases beyond this degree in a warm air furnace, it will cause an uncomfortable condition for the occupants of the dwelling. Hence, when the temperature remains below that value in my novel structure, it is desirable for the mercury switch 11 to be in such position that the electrodes 13 and 14 are bridged by the mercury 12. Hence, the springs 25 and 26 will be so adjusted that the bellows 53 will not rock the actuating member 28 until such time as the temperature approaches this limit temperature. When this temperature is reached, it is desirable to have the switch 11 rock to its other position in which the mercury 12 does not bridge electrodes 13 and 14. Rocking of the switch 11 and opening of the switch will then result in de-energization of the burner or the fuel supply means or some damper means to cut off the supply of heat. Thereafter the temperature will drop and result in rocking the mercury switch back again to close the switch.

Assume now that a portion of my switch actuating structure should begin to leak for some reason, such as the breaking loose of a connection or some deterioration of the parts thereof. Under these circumstances, the same condition would prevail as under low temperature conditions at the capsule 60 and hence the mercury switch will be in the "on" position. However, at this time, with a leak, the pressure within the bellows 53 will be reduced substantially to atmospheric pressure. It will be noted upon reference to the chart disclosed in Figure 2 that my arrangement has been adapted to operate at its limit control setting of 150° F. slightly in excess of 50 lbs. above atmospheric pressure. Now, if the pressure acting on the bellows 53 is reduced to atmospheric pressure, there is substantially no pressure exerted upon the bellows 53 other than the internal stress due to tension in the bellows itself. The spring 61 therefore will urge the plate 55 toward its lowermost position and thus stretch out the bellows 53.

I have shown an auxiliary linkage for actuating the mercury switch 11 to open position in the event of occurrence of an abnormally low pressure affecting the bellows 53. This means is shown as an L-shaped bell crank 70 mounted on a pivot 70a and having an abutting end 71 which is adapted to engage a plate 72 carried upon the actuating stem 56 when said plate 65 moves below a predetermined normal range of movement. When the end 71 is engaged by the plate 72, the bell crank 70 will be rotated in a counter-clockwise direction. At the upper end of the bell crank 70, a link 74 is secured to a pivot 75. The other end of the link 74 connects to a pin 76 which is secured to the switch carrying arm 16. Hence, by reason of engagement of the end 71 with the abutment plate 72 and the consequent rotation in counter-clockwise direction of the bell crank 70, the link 74 will be moved

towards the left. Such movement will move the switch carrying member 16 to the left and cause the mercury within the tube 11 to move to the right-hand end thereof and break the circuit through the electrodes 13 and 14.

During operation discussed above, the switch actuating member 20 will be in the position shown in the drawing. Hence, to permit movement of the switch mounting arm 16, a strain release mechanism 80 is provided and mounted upon a pivot on the actuating arm 20. The mechanism 80 normally serves to turn the switch "on" under normal operating conditions for the system. This mechanism 80 comprises an arm 81 having an ear 82 to which a spring 83 connects with an ear 84 upon the actuating arm 20. The spring 83 biases the arm 81 of the strain release mechanism 80 clockwise toward the right, and a pin 85 mounted on the member 20 limits the movement of the arm 81 under the tension of the spring 83. However, when the auxiliary switch actuating mechanism comes into operation due to an abnormally low pressure, the arm 81 of the strain release mechanism 80 is pivoted toward the left by the switch actuating pin 18 under force of the bell crank lever 70, thereby permitting the switch 11 to be rotated to its open circuit position. The spring 61 for adjusting the bellows 53 is stronger than the spring 83 in the strain release mechanism 80, so that the spring 61 will overcome the spring 83 to actuate the mercury switch 11 when the base member 29 being limited to the stop member 40 is shown in Figure 1.

In the event that some of the structure may bind or fail to operate due to breakage of parts or due to a slow leak in the bellows, capsule or connecting conduit, I have disclosed additional means for causing the auxiliary switch actuating means to be brought into operation. This additional means is shown as a fusible plug 60a in the temperature responsive capsule 60. The fusible plug may be so selected that it will melt at some predetermined extreme temperature condition. When placed in the bonnet of a furnace such as described above, it may be desirable to have the plug melt at 250°. Hence, if the pressure actuated limit switch is adapted to control at 150°, the plug 60a will not normally be brought into operation and the switch structure will be actuated normally by the bellows 53 and the pressure generated by the gas in the capsule 60 through the normal actuating link 20. If, however, no leak occurs in the bellows or in the connections thereto and some of the actuating linkage should fail, the increase in pressure affecting the bellows 53 would not cause the mercury switch to be actuated to open position. Under such circumstances, the heater would not be turned off and the temperature would rise excessively to an undesirable value. At this time, in order to protect the property from damage which might result from fire, it is desirable to shut down the system. Hence, when the temperature rises to a value of, for example, 250°, the fusible plug 60a will melt out of the capsule 60 and permit the actuating medium therein to decrease in pressure, substantially to atmospheric pressure. At this time, the auxiliary actuating means which rotates the switch upon the occurrence of low pressure will be brought into operation to cause the mercury switch 11 to be rocked in a clockwise direction to unbridge the electrodes 13 and 14. It is seen, therefore, that this structure gives an additional safety feature

which brings into play my auxiliary switch actuating means to cause opening of the switch under extreme temperature conditions.

The plug 60a is also useful in preventing unsafe failure of my device due to the occurrence of a slow leak therein. If such a slow leak should occur, the pressure existing within the capsule 60 might not correctly indicate the temperature adjacent the capsule. If the leak were slow, the pressure within the chamber formed by the bellows 53 and the housing 51 might indicate that the temperature adjacent the capsule 60 was in the safe range, when actually it was unsafely high. Under such conditions, an unsafely high temperature might exist adjacent the capsule 60 without causing operation of the switch 11 to open position. The plug 60a is provided to prevent such an unsafe operation of my device. If the temperature adjacent the capsule 60 exceeds 250°, for example, the plug 60a melts, thereby immediately reducing the pressure inside the capsule to atmospheric pressure, whereupon the spring 61 pushes the stem downwardly and causes opening of the switch 11 through the bell crank lever 70.

From the foregoing disclosure of a preferred embodiment of my invention, undoubtedly others skilled in the art will conceive many modifications and variations thereof. Also, other uses will be found for my control switch. For this reason, I wish not to be limited only to that form shown and described, but by the spirit and scope of the appended claims and the prior art.

I claim as my invention:

- 35 1. In a control device comprising a switch movable between first and second positions by an actuator, the combination of pressure responsive means for moving said actuator, spring means for adjusting the pressure value at which 40 switch actuation will occur, means for varying the pressure acting on said pressure responsive means in response to a controlling condition, a member moved by said pressure responsive means when said pressure is below a desired 45 value, connecting means between said member and said switch, and strain release means upon said actuator, said member when moved causing actuation of said switch and said strain release means thereby preventing stress from being 50 placed upon said actuator.
2. In a temperature responsive pressure operated device, a pivot, a mercury switch mounted for rocking therearound, a pressure motor comprising a bellows, a spring biasing said bellows in one direction, a pressure generating capsule partially filled with a volatile fluid acting on said bellows in the opposite direction, said fluid being completely gasified at normal operating pressures for said device so said pressures will be substantially pressures resulting from temperature variations affecting a gas, and first and second actuating linkages actuated by said motor selectively at different pressures for actuating said control means, said first linkage moving said control 55 means between active and inactive positions under normal pressure conditions, and said second linkage moving said control means from active to inactive positions under subnormal pressure conditions.
- 60 3. In a device of the character described, comprising in combination, control means operable between first and second positions, temperature responsive variable pressure means, an actuating lever operably connected to the said temperature 65 responsive variable pressure means for position-

ing the said control means in the first of its positions at a predetermined high pressure, another actuating lever operably connected to the said temperature responsive variable pressure means for positioning the said control means in said first of its positions at a predetermined low pressure, and automatic biasing means operably connected to said temperature responsive variable pressure means in such a manner as to return the said control means from said first of its positions aforesaid upon a pressure exerted by the said temperature responsive variable pressure means having a value between that of the aforesaid predetermined high and low pressures.

4. In a device of the class described, comprising in combination, a circuit control means operable between closed and open positions, a pivot, a lever pivotally mounted on the said pivot and the said lever for actuating the said control means, temperature responsive expansion means operably connected to the said lever at one side of the said pivot so as to actuate the said lever, a plurality of adjustment springs secured to the said lever at the opposite side of the said pivot so as to resist the expansive force of the said expansion means, the said adjustment springs connected at different points of the said lever and one of the said expansion springs having a greater tension force than another of the said adjustment springs, separate adjustment means for each of the said springs and the said spring of lesser tension being so arranged that adjustment thereof will render a finer tension adjustment for the said lever than adjustment of the said spring of greater tension so as to more accurately regulate the actuation of the said control means, and means operably connected to the said springs for indicating the adjustment thereof.

5. In a temperature responsive pressure operated device, a pivot, a mercury switch mounted for rocking therearound, a pressure motor comprising a bellows, a spring biasing said bellows in one direction, a pressure generating capsule partially filled with a volatile fluid acting on said bellows in the opposite direction, said fluid being completely gasified at normal operating pressures for said device so said pressures will be substantially pressures resulting from temperature variations affecting a gas; a first lever acted on by said motor for rocking said switch, spring means secured to said first lever for adjusting the pressure value at which said switch will be rocked thereby; said first lever rocking said switch to an inactive position when the pressure increases, and said spring means operating said switch to an active position when the pressure decreases, a strain release associated with said first lever, and a second lever acted on by said motor for operating said switch when the pressure diminishes to a predetermined low value, said second lever overcoming said strain release and rocking said switch to its inactive position.

6. In a temperature responsive pressure operated device, a pivot, a mercury switch mounted for rocking therearound, a pressure motor comprising a bellows, a spring biasing said bellows in one direction, a pressure generating capsule partially filled with a volatile fluid acting on said bellows in the opposite direction, said fluid being completely gasified at normal operating pressures for said device so said pressures will be substantially pressures resulting from temperature variations affecting a gas; a first lever acted on by said motor for rocking said switch, spring

means secured to said first lever for adjusting the pressure value at which said switch will be rocked thereby; said first lever rocking said switch to an inactive position when the pressure increases, and said spring means operating said switch to an active position when the pressure decreases, a strain release associated with said first lever, a second lever acted on by said motor for operating said switch when the pressure diminishes to a predetermined low value, said second lever overcoming said strain release and rocking said switch to its inactive position, and supplemental means for causing operation of said second lever upon the occurrence of an undesirable temperature condition.

7. A control device, comprising in combination, a closed chamber having a first portion thereof exposed to a variable temperature and a second portion movable in accordance with the difference between the internal and external pressures acting thereon, a body of fluid within said chamber whose pressure lies within a normal range greater than atmospheric when said variable temperature lies within a corresponding normal range, spring means associated with said second portion to bias it against movement by the normal difference in the pressures acting thereon and to maintain said second portion in a normal position when said pressure lies within said normal range, control means movable between an active position and a safe position, means biasing said control means to its active position, a member attached to the second portion of said chamber for movement therewith, a pair of actuating linkages, each linkage including an element positioned in the path of said member to be engaged thereby upon a movement thereof in one of two opposite directions from said normal position, each linkage also including means effective upon further movement of said element in said one direction as an incident to a change in said pressure from said normal range to move said control means against its bias to its safe position, and a fusible plug in said first portion of said chamber effective upon an increase in said temperature to a value substantially above said corresponding normal range to open said chamber to the atmosphere, thereby insuring operation of said control means to its safe position.

8. A control device, comprising in combination, a closed chamber having a first portion thereof exposed to a variable temperature and a second portion movable in accordance with the difference between the internal and external pressures acting thereon, a body of fluid within said chamber whose pressure lies within a normal range substantially different from atmospheric pressure when said variable temperature lies within a corresponding normal range, spring means associated with said second portion to bias it against movement by the normal difference in the pressures acting thereon, and to maintain said second portion in a normal position when said pressure lies within said normal range, control means movable between an active position and a safe position, means biasing said control means to its active position, a member attached to the second portion of said chamber for movement therewith, actuating means for said control means including an element positioned in the path of said member and operable thereby upon a decrease in the difference between said internal and external pressures to move said control means against its bias to its safe position, and a fusible plug in said first portion of said chamber effective upon an in-

crease in said temperature to a value substantially above said corresponding normal range to open said chamber to the atmosphere, thereby insuring operation of said control means to its safe position.

9. A control device, comprising in combination, a closed chamber having a first portion thereof exposed to a variable temperature and a second portion movable in accordance with the difference between the internal and external pressures acting thereon, a body of fluid within said chamber whose pressure lies within a normal range greater than atmospheric when said variable temperature lies within a corresponding normal range, spring means associated with said second portion to bias it against movement by the normal difference in the pressures acting thereon and to maintain said second portion in a normal position when said pressure lies within said normal range, control means movable between an active position and a safe position, means biasing said control means to its active position, a member attached to the second portion of said chamber for movement therewith, and a pair of actuating linkages, each linkage including an element positioned in the path of said member to be engaged thereby upon a movement thereof in one of two opposite directions, each linkage also including means effective upon further movement of said element in said one direction to move said control means against its bias to its safe position.

10. A control device, comprising in combination, control means operable between an active position and a safe position, means biasing said control means to said active position, a movable member having a normal position, means responsive to a condition indicative of the need for operation of said control means for moving said member in opposite directions from said normal position in accordance with the variations of said condition from a normal range of values, and a pair of actuating linkages, each linkage including an element positioned in the path of said member to be engaged thereby upon a movement thereof in one of said directions, each linkage also including means effective upon further movement of said element in said one direction to move said control means against its bias to its safe position.

11. A control device, comprising in combination, control means operable between an active position and a safe position, means biasing said control means to said active position, a movable member having a normal position, means responsive to a condition indicative of the need for operation of said control means for moving said member in opposite directions from said normal position in accordance with the variations of said condition from a normal range of values, a pair of actuating linkages, each linkage including an element positioned in the path of said member to be engaged thereby upon a movement thereof in one of said directions, each linkage also including means effective upon further movement of said element in said one direction to move said control means against its bias to its inactive position, and strain release means connecting said control means with one of said elements to relieve strain on said linkages when said control means is operated by the other of said elements.

12. A control device, comprising in combination, a closed chamber having a first portion thereof exposed to a variable temperature and a second portion movable in accordance with the

difference between the internal and external pressures acting thereon, a body of fluid within said chamber whose pressure lies within a normal range greater than atmospheric when said variable temperature lies within a corresponding normal range, spring means associated with said second portion to bias it against movement by the normal difference in the pressures acting thereon, and to maintain said second portion in a normal position when said pressure lies within said normal range, control means movable between an active position and a safe position, means biasing said control means to its active position, a member attached to the second portion of said chamber for movement therewith, and a pair of actuating linkages, each linkage including an element positioned in the path of said member to be engaged thereby upon a movement thereof in one of two opposite directions from said normal position, and means effective upon further movement of said element in said one direction as an incident to a change in said pressure from said normal range to move said control means against its bias to its safe position, said biasing means being effective upon restoration of said pressure to its normal range to return said control means to said active position.

13. A control device, comprising in combination, control means operable between an active position and a safe position, means biasing said control means to said active position, a movable member having a normal position, means responsive to a condition indicative of the need for operation of said control means for moving said member in opposite directions from said normal position in accordance with the variations of said condition from a normal range of values, and a pair of actuating linkages, each linkage including an element positioned in the path of said member to be engaged thereby upon a movement thereof in one of said directions, each linkage also including means effective upon further movement of said element in said one direction to move said control means against its bias to its inactive position, said biasing means being effective upon restoration of said condition to its normal range to return said control means to said active position.

14. In a control device, comprising in combination, control means operable between first and second positions, a pressure movable member having a normal position, means responsive to a condition indicative of the need for operation of said control means for moving said member in two directions from said normal position in accordance with the variations of said condition from a normal range of values, first and second actuating linkages, the first linkage being engaged by said member upon movement of the said member in one of the said directions for moving the control means to the first of its positions, and the second linkage being engaged by the said member upon movement of said member in the second of said directions for also moving the control means to said first of its positions, and a plurality of adjustment springs connected at different points to said first linkage means for resisting the movement of the movable member in one of its directions.

15. A control device, comprising in combination, control means operable between a first position and second position, a movable member having a normal position, means responsive to a condition indicative of the need for operation of said control means for moving said member in

first and second directions from its normal position in accordance with the variations of the condition from a normal range of values, a first linkage means, a second linkage means, the responsive means under a change in the condition above the normal range of values moving the movable member in one of said directions engaging the first linkage means thereby actuating the first linkage means for moving the control means to the first of its positions, and the responsive means under a change of the condition below the normal range of values moving the movable member in the second direction engaging the second linkage means thereby actuating the second linkage means for moving the control means to the said first of its positions.

16. A control device, comprising in combination, control means operable between first and seconds positions, means biasing said control means to the first of its positions, a movable member having a normal position, means responsive to a condition indicative of the need for operation of said control means for moving said member in first and second directions from said normal position in accordance with the variations of said condition from a normal range of values, first linkage means, second linkage means, the responsive means under a change in the condition above the normal range of values moving the said movable member in the first direction engaging the first linkage means thereby actuating the first linkage means for moving the control means to the second of its positions, and the responsive means under a change in the condition below the normal range of values moving the movable member in the second direction engaging the second linkage means thereby actu-

ating the second linkage means for moving the control means to said second of its positions, and said biasing means being effective upon restoration of said condition to its normal range to return said control to the first of its positions.

17. A control device, comprising in combination, control means operable between first and second positions, means biasing said control means to the first of its positions, a movable member having a normal position, means responsive to a condition indicative of the need for operation of said control means for moving said control member in first and second directions from said normal position in accordance with the variations of said condition from a normal range of values, first linkage means, second linkage means, the responsive means under a change in the condition above the normal range of values moving the movable member in the first direction to engage the first linkage means thereby actuating the first linkage means for moving the control member to the second of its positions, and the responsive means under a change in the condition below the normal range of values moving the movable member in the second direction to engage the second linkage means thereby actuating the second linkage means for moving the control means to the second of its positions, a strain release means connecting said control means to the first linkage to relieve the strain on said linkage and said control means when the control means is actuated by the second linkage means, and said biasing means effective upon restoration of said condition to its normal range of values to return said control means to the first of its positions.

CARL G. KRONMILLER.
